FUNNEL GUIDE MOUNTING

Hugh D. Haley, Drexel Hill, and Hiram D. Schaffer, Boothwyn, Pa., assignors to American Viscose Corporation, Wilmington, Del., a corporation of Delaware

Application January 31, 1945, Serial No. 575,448

8 Claims. (Cl. 57—76)

1

This invention relates to an improved funnel guide mounting. More particularly the invention relates to a mounting for the funnel through which filamentary material, produced in accordance with the viscose process, for example, may be led into a spinning bucket in which it is collected in the form of an annulus.

The invention is concerned especially with funnel mountings of the type shown in Rushton 1,672,691 adapted to swing the funnel into operative position in the spinning bucket, and to swing the funnel clear of the bucket when a "cake" of filamentary material collected therein is ready for doffing.

The type of mounting of which the present invention is an improvement comprises a support adapted to be secured to the traverse rail of a spinning machine, means for holding the funnel, and two parallel pairs of arms arranged between the support and funnel holding means, and pivotally connected to each of them. In funnel mountings of the general type described which have been available prior to the present invention, the arms connecting the support and funnel holding means have been pivotally mounted on the support and holding means by pivots which also constitute part of the means for adjusting the tightness of the joints between the arms and connected parts. In addition, such adjusting means have been located in exposed positions where they have been subject to corrosion by the acid escaping from the spinning machine.

Experience has shown that because of the corrosive effects of the acid in the neighborhood of the machine, the joints of the funnel mountings become stiff and unworkable after only short periods of use, and require constant readjustment. Further, since the pivots and adjusting means are interdependent, the constant swinging of the arms on their pivots has a loosening effect on the joints so that even when the parts are not corroded, retention thereof in a predetermined tight but relatively movable condition requires constant readjustment.

It is a primary object of the present invention to provide a swingable funnel mounting which functions smoothly and maintains its tightness at all times over long periods of use. Another object is to provide a funnel mounting of the type described in which the means for tightening the joints is independent of the pivotal means connecting the pairs of parallel arms to the support and to the funnel holding means. A further object is to provide a stream-lined funnel mounting in which the number of exposed movable

2

parts is reduced. Other objects and advantages of the invention will be apparent from the following description when read in conjunction with the accompanying drawing, in which

5 Figure 1 is a side elevation of the improved funnel mounting, in which the operative position is shown in solid lines, and the inoperative position is shown in broken lines;

10 Figure 2 is a plan view of the improved mounting; and

Figure 3 is a view taken on line III—III of Figure 2.

In the drawing there is shown a portion of a 15 spinning bucket 2 provided with a cover 3. A traverse rail 4 is provided to impart relative vertical reciprocal movement between the spinning bucket 2 and the funnel guide 5 for laying the filamentary material in a series of layers against the inside wall of the bucket. The filamentary

20 material is introduced into the bucket through funnel 5 having a stem 6 extending into the bucket through aperture 7 in cover 3. The holding means for the guide 5 comprises a threaded bushing 12, an extension 9 of a movable member 10, and the nuts 8 for adjustably holding the 25 guide and bushing in fixed position on the extension 9. Secured to traverse rail 4 by bolts 13 is a support 14. Support 14 is connected with movable member 10 of the funnel holding means

30 by two pairs of arms 15 and 16 arranged in parallel relation one pair above the other, each pair of arms being pivotally connected to support 14 and movable member 10 by means of pivot pins 17. The pivot pins project from the inner faces 35 of the arms into bores in support 14 and member 10, so that when the device is assembled, the pivot pins are entirely enclosed within the arms and support 14, and within the arms and member 10. The two arms constituting each pair are

40 adjustably joined together by shouldered studs 18 which screw into threaded holes 19 in the inner faces of the arms. The ends of the studs are threaded oppositely that is one end is left-hand and the other right-hand so that turning of the 45 knurled portion intermediate the shoulders tightens or loosens the connection between the stud and the pair of arms. Gaskets 20 may be provided between the arms and the shoulders of studs 18. Studs 18, which in cooperation with

50 the threaded holes in the sides of the arms, afford a ready means of simultaneously adjusting the relation of the two arms 15 and the two arms 16 as to set the joints in any desired tightness, are disposed intermediately of and independently of the pivot pins 17 whereby the arms are con-

nected to support 14 and member 10. The studs are readily available for adjustment by the operator. The pivotal movement of the arms on the support 14 and member 10 of the funnel holding means does not affect the studs or exert friction thereon, causing undue wear or loosening thereof, and the parts are retained in the adjusted position until changed by the operator. The pivot pins which are entirely enclosed within the arms and support 14 and member 10, are not effected by acid escaping from the spinning machine, so that the arms remain freely swingable over an indefinite period of time and the funnel mounting does not become stiff or unworkable. The funnel mounting may be constructed in its entirety of any suitable acid resisting material, such as a resinous material of the type of Bakelite or Durez, for instance and, preferably, pivot pins are molded or otherwise formed integrally with the arms 15 and 16.

Modifications may be made in the apparatus disclosed herein without departing from the spirit and scope of the present invention which is not to be limited except as necessitated by the appended claims.

We claim:

1. A guide mounting comprising means for holding the guide, a support, and two pairs of arms arranged therebetween in parallel relation one pair above the other, pivotal means connecting adjacent ends of the arms with the support, pivotal means connecting the other adjacent ends of the arms with the guide holding means and means independent of the pivotal connections disposed intermediately of each pair of arms for adjustably joining the arms together.

2. A guide mounting comprising means for holding the guide, a support, and two pairs of arms arranged therebetween in parallel relation one pair above the other, pivotal means connecting adjacent ends of the arms with the support and being entirely enclosed within the arms and support, pivotal means connecting the other adjacent ends of the arms with the guide holding means and being entirely enclosed within the arms and guide holding means, and means independent of the pivotal connections disposed intermediately of each pair of arms for adjustably joining the arms together.

3. A guide mounting comprising means for holding the guide, a support, two pairs of arms arranged therebetween in parallel relation one pair above the other, pivot pins connecting adjacent ends of the arms with the support and being entirely enclosed within the arms and support, pivot pins connecting adjacent ends of the arms with the guide holding means and being entirely enclosed within the arms and guide holding means, and means independent of the pivot pins disposed intermediate the ends of each pair of arms for adjustably joining the two arms of each pair together.

4. A guide mounting comprising means for holding the guide, a support, two pairs of arms arranged therebetween in parallel relation one above the other, the arms of each pair being disposed on opposite sides of the support and guide holding means, pivotal means connecting each pair of arms with the support and being entirely enclosed within the arms and support,

pivotal means connecting each pair of arms with the guide holding means and being entirely enclosed within the arms and guide holding means, and means independent of the pivotal means for adjustably joining the two arms of each pair together.

5. A guide mounting comprising means for holding the guide, a support, two pairs of arms arranged therebetween in parallel relation one above the other, pivotal means connecting adjacent ends of the arms with the support and being entirely enclosed within the support, pivotal means connecting adjacent ends of the arms with the guide holding means and being entirely enclosed within the arms and guide holding means, and studs disposed intermediately of and independently of the pivotal means for adjustably joining the two arms of each pair together.

6. A guide mounting comprising means for holding the guide, a support, two pairs of arms arranged therebetween in parallel relation one above the other, pivotal means connecting adjacent ends of the arms with the support and being entirely enclosed within the support, pivotal means connecting adjacent ends of the arms with the guide holding means and being entirely enclosed within the arms and guide holding means, and shouldered studs disposed intermediately of and independently of the pivotal means for adjustably joining the two arms of each pair together.

7. A guide mounting comprising means for holding the guide, a support, two pairs of arms arranged therebetween in parallel relation one above the other, pivotal means connecting adjacent ends of the arms with the support and being entirely enclosed within the arms and support, pivotal means connecting adjacent ends of the arms with the guide holding means and being entirely enclosed within the arms and guide holding means, studs disposed intermediately of and independently of the pivotal means connecting the arms with the support and guide holding means and threaded holes in the arms adapted to receive the studs to join the two arms of each pair together and permit simultaneous adjustment of the joined arms.

8. A guide mounting comprising means for holding the guide, a support, two pairs of arms arranged therebetween in parallel relation one above the other, one arm of each pair being disposed on one side of the support and guide holding means, and the other arm of each pair being disposed on the opposite side of the support and guide holding means, pivot pins connecting the arms of each pair with the support and being entirely enclosed within the arms and support, pivot pins connecting the arms of each pair with the guide holding means and being entirely enclosed within the arms and guide holding means, studs disposed intermediately of and independently of the pivot pins connecting the arms with the support and guide holding means, and threaded holes in the arms adapted to receive the studs to join the two arms of each pair together and permit simultaneous adjustment of the joined arms.
